VOICE CURRENT REPEATER

Filed Sept. 2, 1930

UNITED STATES PATENT OFFICE

HOWARD H. SMITH, OF CHICAGO, ILLINOIS, ASSIGNOR, BY MESNE ASSIGNMENTS, TO
ASSOCIATED ELECTRIC LABORATORIES, INC., OF CHICAGO, ILLINOIS, A CORPORATION
OF DELAWARE

VOICE CURRENT REPEATER

Application filed September 2, 1930. Serial No. 479,253.

This invention relates to voice current repeaters in general, but in particular to voice current repeaters of the switching type which are capable of two-way repetition in long distance telephone lines. The principal object of this invention, briefly stated, is the provision of a switching type repeater which is exceedingly rapid and reliable in its operation and which is particularly adaptable for operation in telephone circuits in which are included composite telegraph sets for telegraph operation.

One feature of the invention is the arrangement whereby heater type tubes may be used in the repeater without any loss of speech because of the normal time required for tubes of that type to reach the effective operating temperature.

Other objects and features of the invention will be apparent from the accompanying single sheet of drawing and the following description.

In the drawing, there is diagrammatically depicted by means of usual circuit symbols, a voice current repeater constructed in accordance with this invention. This repeater is provided with a transmission path for each direction of travel of the voice currents through the repeater and each transmission path includes what will hereinafter be termed a line amplifier which amplifies and repeats the voice current for conversational purposes.

These line amplifiers are normally conditioned to receive voice currents in the proper direction, but are normally prevented from repeating them until a switching operation takes place to close their normally open output circuits. Each line amplifier has associated with it a switching amplifier, the output of which is used solely to operate a voice current relay to perform the aforementioned switching operations.

In order that the direction of travel of voice current may readily be seen, that portion of the telephone trunk, or line, which is shown connected to the repeater at the left side of the drawing is termed line "west", while that at the right is termed line "east". Likewise, that line amplifier and that switch-

ing amplifier for "west-to-east" transmission will be called the "west-east" amplifiers, while those for "east-to-west" transmission will be called "east-west" amplifiers.

In constructing the repeater of this invention, vacuum tubes of the four-prong heater type have been used. As is known by those acquainted with heater type tubes, it is a matter of seconds after current has been connected to the heating elements before the operating temperature of the tube is reached. Thus it can be seen that if such tubes are used in voice current repeaters without being preheated, the result would be the loss of a considerable portion of the initial speech. According to this invention, this preheating arrangement has been taken care of by supplying a common battery as the source of "A" current for all of the tubes of the various amplifiers, the current from which battery is supplied to the filaments of the tube through a resistor when the repeater is not in use, so that the tubes will receive only sufficient current to keep them heated for immediate operation. A low resistance circuit around said resistor and means for closing that circuit when the repeater is taken into use have been provided in order that the filaments may obtain the full voltage for operation. By this arrangement, no time is lost because of cold tubes and the repeater will function immediately when taken into service.

When the repeater is taken into use, it is placed in operating condition by the operation of key K which completes the circuit of start relay 3. In a manual telephone system, this key K is located at an operator's position. The ground supplied to the winding of relay 3 by key K may, as an alternative, be supplied through the sleeve contacts of plug and jack connections to the trunk when it is desired to establish a telephonic connection between two terminating stations. In an automatic telephone system, seizure of this trunk by an automatic switch will cause the application of ground to the winding of relay 3.

However, regardless of how the ground is supplied to relay 3, that relay operates when its circuit is completed and at its armature 11 completes the low resistance path about

the resistor R1, in order that the tubes of the amplifier will be supplied with the full voltage output of battery A. It will here be noted that when the repeater is not in use, 5 the filaments of the tubes obtain current from the battery A through the variable resistor R and the fixed resistor R1 over conductor 10 sufficient to keep the filaments heated. The variable resistor R is for the purpose of regulating the supply of operating current to the tubes.

It has been discovered that the heater type vacuum tubes now available commercially will only operate as amplifiers when used as 15 contemplated by this invention if the plate voltage has been greatly increased or, preferably if a positive potential has been placed upon the grid. Accordingly, a battery D has been shown at each end of the drawing with 20 its positive terminal connected in the grid circuits of all of the tubes comprising the line and switching amplifiers at the respective ends of the drawing. These batteries D supply the necessary positive potential to the tubes to render them operative.

Further results of the operation of relay 3 are the connection of the plate or space current from battery B to the plates of the vacuum tubes by way of armature 13 and its make 30 contact and conductor 16, and the connection of ground G to the windings of the remainder of the relays and to the vibrating contacts of relays 5 and 5' by way of armature 12 and its make contact. It will be noted in the drawing 35 that all ground connections supplied from ground G through armature 12 have been represented by encircled ground symbols. This has been done to simplify the drawing in order that the invention might not be obscured by multiplicity of lines leading from the make contact of armature 12 to these various relays.

When ground is so connected by relay 3 through its armature 12, the upper windings 45 of relays 1, 5 and 6 and the lower windings of relays 2, 5' and 6' energize in the obvious circuits, while the middle windings of relay 5 and 5' energize through the normally engaged contacts of relays 4 and 4', respectively. 50 Also, the lower winding of relay 6 and the upper winding of relay 2 are energized through the contacts of relay 4, armature and resting contact of relay 5, thence by way of conductor 7, while the upper winding of relay 6' and the lower winding of relay 1 are energized through the contacts of relay 4', 55 armature and resting contact of relay 5', and thence by way of conductor 7'.

Relays 1, 2, 5, 5', 6 and 6' are balanced differential relays, that is, the two windings have equal and opposite effects and thereby neutralize each other when energized at the same time. Therefore, when the two winding of each of these relays are energized simultaneously, the relays remain inert. The

third windings of relays 5 and 5' are employed to make those relays slow-to-release in the well known manner.

Therefore, with the exception of relay 3, the connection of ground through the winding of the relay 3 leaves the equipment in the condition in which the parts are shown in the drawing. However, since the amplifiers are now receiving their full supply of "A" current and since the "B" current has been 75 connected to the plate and the various relays have been energized, the repeater is in condition to repeat voice currents in either direction.

Assuming, now, that voice currents commence to flow in the "west-east" direction, they will be received by the repeater over line "west" and through the "west" repeating coil RW. Since relay 1, although both windings are energized, is in the position shown, the 85 voice currents will be induced in the primary winding of transformer T. As can be seen by the drawing, the "west-east" line amplifier and the "west-east" switching amplifier are connected in parallel to the secondary winding of the transformer T. Therefore, both 90 of these amplifiers receive voice currents through the transformer T.

Connected in the output circuit of the two switching amplifiers are the voice current relays 4 and 4'. These relays are sensitive to voice currents to vibrate their contacts in the same manner as the type of relay disclosed in United States Patent No. 1,221,299, issued to C. J. Erickson, on April 3, 1917.

Since relay 4 is in the output circuit of the "west-east" switching amplifier, it will respond to the voice currents magnified by that amplifier by vibrating its contacts to remove ground from the middle winding of relay 5 and from the conductor 7. As a result, relays 5, 6 and 2 are unbalanced and immediately attract their armatures into engagement with their make contacts. The attraction of the armature of relay 2 connects the secondary winding of the output transformer T1 of the "west-east" line amplifier to the "east" line repeating coil RE by way of conductors 8 and 9, thereby completing the "west-east" transmission, or repeating, 110 circuit through the repeater. This attraction of the armature of relay 2 also disconnects the input transformer T' of the "east-west" line and switching amplifiers from the "east" line repeating coil RE and the line "east" in 115 order that the "west-east" transmission path may be maintained without interruption as long as voice currents flow in that direction.

Relay 5 in attracting its armature out of engagement with its resting contact opens 125 at that point the circuit of the lower winding of relay 6 and the upper winding of relay 2 to prevent restoration of these relays until relay 5 restores. Engagement of the armature of relay 5 with its make contact com-

pletes the circuit of the third or lower winding of that relay to establish a path for eddy currents to make relay 5 slow-to-release.

Relay 6 in attracting its armature into engagement with its make contact connects ground to conductor 15, thereby locking relays 5' and 6' against chance operation of the vibrating contacts of relay 4'.

Because of the slow-to-release feature of relay 5, this relay will remain operated for a short interval after the contacts of relay 4 cease vibrating following the cessation of voice currents in the "west-east" direction. This interval during which relay 5 remains operated is greater in length than the ordinary pause between words in conversation in order that the relay 5 will remain operated during such pauses, thereby maintaining its armature attracted to prevent the disruption 20 of the "west-east" transmission circuit through the repeater.

When the vibrating contacts of the voice current relay 4 remain quiet for a period greater in length than the time required for relay 5 to restore, relays 6 and 2 restore because of the neutralizing effect of their windings when ground has been reconnected to conductor 7, thereby restoring the original condition of the repeater for reception of voice currents from either direction.

Since the input transformer T' is now connected to the "east" line repeating coil RE, voice currents traveling in the "east-west" direction will be received by the "east-west" line and switching amplifiers. Voice current relay 4' will now be operated from the output of the "east-west" switching amplifier and will vibrate its contacts to control relays 5', 6' and 1 in the identical manner in which relays 5, 6 and 2 were controlled by the voice current relay 4. The output amplifier T' of the "east-west" line amplifier is now connected by way of conductors 8' and 9' and armature and make contact of relay 1 to the "west" line repeating coil RW and line "west", while the input transformer T of the "west-east" amplifiers is disconnected from repeating coil RW so that a one-way transmission or repeater circuit in the direction "east-west" is established through the repeater.

It will be noted that the voice current relay 4' is impedance-coupled to the "east-west" switching amplifier. This coupling consists of the retard coil I and the condenser C and comprises what is termed a "thump filter" which is of such an impedance as to suppress the low telegraphic frequencies, or thump frequencies, and to favor the high voice current frequencies. By this arrangement chance operation of the relay 4' or interference in its operation by telegraphic frequencies is eliminated.

Connection of ground to conductor 14 by relay 6' prevents the chance operation of relays 5 and 6 when the "east-west" transmis-

sion circuit has been established through the repeater.

The third or upper winding of relay 5' makes this relay slow-to-release also for the purpose of maintaining the "east-west" repeater circuit during ordinary pauses in conversations such as those between words.

Throughout the conversation period the repeater will function to first establish a transmission path through it in one direction and then establish another transmission path through it in the opposite direction as long as conversation between the two terminating stations takes place.

When the conversation is terminated, the operator will release the key K to restore relay 3, this relay thereupon at its armature 13 disconnects the source of "B" current from the plates of the vacuum tubes and at its armature 12 removes ground from the windings of the relays and the contacts of the voice current relays so that when the repeater is not in use there will be no unnecessary drain upon the batteries. At its armature 11, the relay 3 removes the shunt from about the resistor R1 so that the current applied to the filaments of the vacuum tubes is reduced, but not entirely removed.

Bridged across the input circuits of the line amplifiers are the gain control devices GC and GC', which are adjustable to obtain the desired amount of gain of the amplifiers.

It will now be appreciated that a two-way voice current repeater of the switching type may be constructed to use heater type vacuum tubes in such a way that no loss is sustained for the necessary heating of the tubes before the repeater can function. It will also be appreciated that here is a voice current repeater which can be used with any telephone line without the necessity of providing a balancing network and especially with a telephone line which has composite telegraph sets included therein for telegraphic transmission over the line.

Having thus described this invention, what is considered new and what is desired to have protected by Letters Patent is pointed out in the appended claims.

What is claimed is:

1. In a two-way repeater circuit, the combination of two repeaters, each having an incoming and outgoing section, the outgoing section of each repeater being normally open, the incoming section of each repeater having an amplifying device for magnifying voice currents for conversational purposes, a second amplifying device for each repeater for magnifying voice currents for switching purposes, a switching relay for each outgoing section, and a voice current relay associated with each of said second amplifying devices and responsive to the voice currents magnified thereby for operating the switching relay of the associated outgoing section.

to open the incoming section of the other repeater and to close said associated outgoing section, and means associated with each repeater and controlled by the associated 5 voice current relay for locking the other repeater against chance operation.

2. In a two-way repeater circuit, a voice current amplifier for each direction of repetition through said circuit, each amplifier 10 having a normally open output circuit, a circuit closing device for each output circuit, means individual to each amplifier and responsive to an initial voice current in the proper direction to operate the circuit closing device of the associated amplifier to close the output circuit thereof, and other means 15 associated with each amplifier and responsive to the operation of the first-mentioned means individual to the associated amplifier to prevent operation of the first-mentioned means 20 individual to the other amplifier while the output circuit of the associated amplifier is closed.

3. In a two-way repeater circuit, a current 25 amplifier for each direction of repetition over the circuit having a normally open output circuit, a normally balanced differential relay associated with each amplifier and having means for closing the output circuit of 30 the associated amplifier when the relay is unbalanced, a voice current relay individual to each amplifier and responsive to voice currents delivered to the associated amplifier to unbalance the differential relay of the 35 associated amplifier to thereby close the output circuit thereof, and a second balanced differential relay associated with each amplifier and also unbalanced by the voice current relay individual to the associated amplifier 40 responsive to voice currents being delivered thereto to prevent unbalancing of the first mentioned differential relay associated with the other amplifier while the output circuit of the associated amplifier is 45 closed.

In witness whereof, I hereunto subscribe my name this 28th day of August, A. D. 1930.

HOWARD H. SMITH.
